Patented Jan. 27, 1914.

UNITED STATES PATENT OFFICE.

FRANK DI GIANNI, OF MUSCATINE, IOWA, ASSIGNOR TO MUSCATINE PEARL NOVELTY COMPANY, OF MUSCATINE, IOWA, A CORPORATION OF IOWA.

SHELL-GRINDING MACHINE.

1,085,381.

Specification of Letters Patent. Patented Jan. 27, 1914.

Application filed January 27, 1913. Serial No. 744,422.

To all whom it may concern:

Be it known that I, FRANK DI GIANNI, of Muscatine, in the county of Muscatine and State of Iowa, have invented certain new and useful Improvements in Shell-Grinding Machines; and I hereby declare that the following is a full, clear, and exact description thereof, reference being had to the accompanying drawings, which form part of this specification.

This invention is a novel machine for grinding pieces of shell and the like in irregular form, it being especially designed for use in grinding pieces of pearl shell into brooches, pins, fobs, buckles, and other ornamental articles.

The invention consists in the novel construction of the means for presenting the shell to the grinder so that it can be ground to the desired form without any particular attention on the part of the operator other than to rotate the shell support so as to present the shell edgewise to the grinder; and such means is illustrated in the accompanying drawing and hereinafter described.

In said drawings—Figure 1 is a top plan view of the shell grinding machine, partly broken away. Fig. 2 is an end elevation of Fig. 1, partly broken away. Fig. 3 is a detail section on line 3—3, Fig. 1. Fig. 4 is a detail view of one of the cams.

The machine comprises a head plate 1, which is preferably formed with a longitudinal dove-tailed groove in its upper side, 35 in which groove is mounted a slide 2, and said slide is normally projected outwardly by means of a spring 2^a interposed between the outer end of the side and a cap plate 1^a attached to the outer end of the plate 1 as shown. Attached to said slide, and supported thereby above the upper surface of the plate 1, is a transverse bearing 2^b for a shaft 3; and this shaft may be removably secured in position in the bearing 2^b by 40 having the cap-plate 2^c detachably secured to the base bearing plate by tap bolts so that by removing the cap-plate 2^c the shaft 3 can be bodily removed from the bearing. This shaft 3 is provided, preferably at each 45 end of the bearing, with a cam 3^a. These cams correspond in external contour to the external contour which it is desired to impart to the shell object. As illustrated the cams are of shield-shape and the shell S

will be reduced to a similar shape, as indicated by the dotted lines in Fig. 3.

In practice interchangeable sets of cams 3^a of different shapes may be provided, one cam or set of cams for each shape of shell which it is desired to produce by the machine; such cams may be detachably attached to the shaft 3 in any well known manner; or if desired the cams may be permanently attached to shafts 3, and such cammed shafts be interchangeable. The peripheries of the said cams 3^a are adapted to engage with rollers 4^a on studs 4 attached to brackets 4^b secured to the sides of the plate 1, or formed therewith. The spring 2^a acting on slide 2 normally keeps the peripheries of the cams 3^a in contact with the rollers 4^a; the slide 2 moving forward or back according as the cams permit it to move under the action of the spring 2^a or compel it to move against such spring.

One end of the shaft 3 may be provided with a shell clamp 3^c of any suitable construction, to hold a piece of shell S parallel with the cams 3^a and perpendicular to the shaft 3. Ordinarily the piece of pearl or shell to be shaped has an opening through it, which opening corresponds with a stud 3^d on the clamp head and the shell S is held endwise against the clamp by means of a screw 3^e, or in any other convenient way. The particular means for clamping the shell to the shaft 3 is not a feature of the invention.

Adjacent the clamp 3^c is a grinder 5, which may be of carborundum or other suitable material, mounted on a spindle 5^a which can be driven by a belt 5^b, or in any other suitable manner. The shaft 3 may be rotated manually by means of a handle 3^c.

The slide 2 may be retracted by means of a lever 6 pivoted at 6^a upon the standard 1^a on which plate 1 is supported; and lever 6 may be operated by hand, or may be connected by a rod 6^b to a treadle lever, not shown, so that it can be operated by the foot when it is desired to retract the slide 2 and withdraw the shell from the grinder 5, against the resistance of spring 2^a. The standard 1^a and the spindle of the grinding wheel 5 may be mounted upon a base 7 in any suitable way, so as to hold the said parts in relatively fixed relation.

Operation: When the parts are in the po-

sition indicated in Fig. 1, and a shell S attached to the end of the shaft 3, said shell will be pressed edgewise into contact with the grinder 5 by the action of the spring 2^a 5 on the slide 2, which slide moves the shaft cam and shell bodily, as indicated in the drawing. The movement of the slide will be arrested first by the contact of the edge of the shell with the grinder 5; but as the 10 grinder is rotated the shell is cut away and the slide advances the shell toward the cutter until the forward movement of the slide is arrested by contact of the cam or cams 3^a with rollers 4^a. The operator should turn 15 shaft 3 slowly, by means of the handle 3^a, and thus present the entire edge of the shell to the grinder, and the latter cuts away the shell until it conforms in shape to the shape of the cams, as will be readily understood 20 from the drawing. The piece of pearl or shell S attached to clamp 3 is preferably roughly shaped, before it is attached thereto, so as to reduce the time and amount of 25 grinding required.

It will be seen that by having interchangeable cams, or shafts and cams, the shells may be cut of any desired form or outline; when the operator can rotate shaft 3 without any further grinding contact between the grinder 30 and shell the work is completed, and the

shell will be of the form of the cams; then by depressing the lever 6 the slide 2 is retracted, moving the finished shell away from the grinder, and another piece of shell can be operated upon. The cams, or cams and 35 shaft, can be removed and substituted by others to produce the desired shape of shell.

What I claim is:

The combination with a support, a grinder 40 rotating on a vertical axis, a slotted plate on said support, a slide movably mounted in the slot of said plate, a manually rotatable changeable shaft mounted horizontally on and transversely of said slide, a pair of cams 45 fixed on said shaft at opposite sides of the slide, members attached to the support adjacent the slide and engaging said cams, a clamp on the outer end of said shaft for securing a shell thereto; a spring engaging said slide to cause the shaft to yieldingly 50 hold the shell against the grinder, and a lever and connections for retracting said slide, substantially as described.

In testimony that I claim the foregoing as my own, I affix my signature in presence of 55 two witnesses.

FRANK DI GIANNI.
